PERFORATING DEVICE

Samuel Segal, New York, N. Y., assignor to Wilson-Jones Co., Chicago, Ill., a corporation of Massachusetts

Application July 13, 1945, Serial No. 604,906

16 Claims. (Cl. 164—91)

1

The subject matter of this invention is a perforating device wherein one or more vertically guided punching tools are operated by a rotatable shaft driven by a manually controlled handle. In perforating devices of the type alluded to standards are employed to rotatably and slidably guide the driving shaft.

One object of the invention is to provide means for readily and quickly assembling the standards to the base of the perforating device. Another object is concerned with stabilizing the base of the perforating device in the provision of a concealed reinforcing block to which the standards are removably connected. Another object is to employ a swingable receptacle for collecting paper leavings incidental to perforating operations and to utilize these leavings to cooperate with the punching tools to open the receptacle. A further object is concerned with a floating stud to resist removal of the driving shaft from the standards. A still further object is to provide serviceable means for removably holding the manually controlled handle depressed to conserve space. Another object has to do with a novel paper gage bar adapted to be conveniently adjusted relative to the base of the perforating device. A further object is to provide a simplified perforating device, sturdy and reliable in operation and capable of low cost of manufacture. Other important objects and functional and structural advantages will appear from the following detailed description taken with the accompanying drawings wherein:

Fig. 1 is a plan view of the perforating device according to one form of my invention.

Fig. 2 is a bottom view of Fig. 1.

Fig. 3 is a front elevational view of Fig. 2 illustrating the operating lever held depressed.

Fig. 4 is a transverse sectional view on the line 4—4 of Fig. 2 showing in full lines the normally closed position of the waste collecting pivoted receptacle and in dash lines the open relation thereof.

Fig. 5 is a transverse sectional view on the line 5—5 of Fig. 4.

Fig. 6 is a transverse sectional view on the line 6—6 of Fig. 1 illustrating the retaining pin in a lowered position and cooperating with one of the standards to prevent longitudinal displacement of the rotatable driving shaft.

Fig. 7 is an enlarged fragmentary view of Fig. 6.

Fig. 8 is a fragmentary view of the waste collecting receptacle.

Fig. 9 is a transverse sectional view on the line 9—9 of Fig. 8.

2

Fig. 10 is a sectional view on the line 10—10 of Fig. 2.

Fig. 11 is a fragmentary view of Fig. 2 however illustrating another form of locking means for the slidably guided gage bar.

Fig. 12 is a view similar to Fig. 1, shown partly broken away and illustrating a fixed stud carried by the oscillatable shaft to prevent or permit withdrawal of the latter from the standards.

Fig. 13 is a fragmentary view of Fig. 12, and Figs. 14 and 15 are transverse sectional views on the lines 14—14 and 15—15 of Fig. 13 respectively.

The perforating device P comprises a one piece base B having the rectilinear top wall 10 and the depending rim embodying the curved front wall 11, the rear wall 12 and the side walls 13 and 14.

Secured to the inner surface of the top wall 10 is the reinforcing plate or block 15 having the intermediate relatively thickened portion or depending boss 16 from which extend the front and rear attenuated webs 17 and 18. The reinforcing metal block 15 and webs 17 and 18 extends across substantially the entire length of the base and are firmly secured by spot welding the webs 17 and 18 to wall 10. Thus a sturdy and durable reinforced base is provided.

Mounted on the top wall 10 of the base are a plurality of headers or standards S each provided with upper and lower lobes 19 and 20 (Figs. 3 and 4) having vertically aligned bores 21 and 22 for slidably guiding cylindrical perforating members generally designated 23 which include depending reduced cylindrical punching portions 24 slidably guided in aligned bores 25, 26 and 27 in the lobes 20, the top wall 10, and the reinforcing plate or block 15.

The standards S are removably clamped on the base B by stud screws 28 having its threaded shank adapted to pass into the aligned openings or bores 30, 31, and 32 in the stabilizing or reinforcing block 15, the top wall 10, and the body of the standards respectively.

The bores 32 in the standards are threaded and cooperate with the threaded shanks of the set screws 30 whereby the heads 33 may be desirably clamped against the reinforcing blocks 15 for drawing the standards in a clamped relation against the top of the base. By this arrangement, assembly of the standards with the base is convenient and facilitated. Should any of the standards be rendered ineffective it may be thus quickly removed and a new standard substituted.

Normally the punching members or tools 23 are held in an elevated position, namely, with

their reduced punching portions 24 as shown in Fig. 4, that is, out of the gap G by the action of the helicoidal springs 34 surrounding the reduced portions 24 of the perforating tools 23. These springs are confined within the bores 22 of the lower lobes 20 and have their terminals abutting shoulders 35 of the punching tools and the annular lips 36 of the lower lobes 20.

Merging with the upper and lower lobes 19 and 20 of a standard is the circular cutaway portion or semi-circular bore 37 which characterizes bearing means. With the standards S clamped and held on the base, bearings 31 are in alignment and rotatably and removably guide the driving shaft 38 provided with a longitudinally arranged groove 39 defining diverged upper and lower lips 40 and 41 which straddle or operatively interlock with the several ribs 42 extending from the punches 23 into the groove 39. It follows that if the handle or crank H which is fixedly fastened to the driving shaft 38 be depressed or elevated, this shaft is rotated clockwise or counterclockwise. If depressed the upper lip 39 of the drive shaft actuates the ribs 42 of the slideable punching tools 23, thus driving the punching portions downwardly against the resistance offered by springs 34, across gaps G and into the aligned bores or openings 26 and 27 in the top wall of the base and reinforcing strengthening plate 15. By this action, sheets of paper or the like mounted on the base will be perforated or punched. Once however manual pressure is removed from the handle, the punching tools 23 which incidentally are of suitable tool steel are raised automatically due to the expansion of the springs 34. Because of such action, ribs 42 of the punching tool 23 are elevated, thus reversing rotating the grooved shaft 38 and the handle H is again restored to its normally raised position at which time the reduced portion 24 of the punching tools are clear and free of gap G, hence a stack of papers may be again mounted on the top wall or platform 19 of the base and positioned into the gaps G.

Disc portions or leavings 44 are severed from the sheets of paper on perforating the latter. These accumulate in the pan or receptacle 50 and are ejected from the bore 27 of the reinforcing or stabilizing block 15. The receptacle 50 is swingably mounted within the rim of the base B and is rectangularly shaped and is substantially coextensive with the length of the base. Specifically it embodies the forwardly projecting spaced ears 51 each of which is provided with a struck out hollow boss or nipple 52 (Fig. 5) rotatably journaled in the bearings or openings 53 in the spaced sides 13 and 14 of the rim of the base B. It follows that the nipples are rotatably retained and hence the receptacle is swingably sustained within the base, being retained in its closed position by the offset spring detents 54 struck out of the sides 55 and 56 of the receptacle frictionally but removably cooperating with the spaced sides 13 and 14 of the base.

As the paper leavings 44 accumulate in the receptacle, eventually they cooperate with the punching tools 23 to overcome the frictional resistance created by the detents or spring locks 54 against the sides 13 and 14 of the pan or base 10, consequently causing the pan 50 to tilt downwardly and forwardly, pivoting on the spaced trunnions or nipples 52. By such action indicator means is established that the pan should be emptied. After disposal of the leavings 44 the pan is again swung upwardly or closed and such

position is maintained by the frictional lock imparted by detents 54 against the sides 13 and 14 of the base.

According to the invention a gage bar 60 is utilized. This bar is slidably guided longitudinally of the base by spaced straps 61 and 62 spot welded to the underneath face of the top wall 10 of the base and/or the flange 17 of the reinforcing block 15. The gage bar includes a plurality of notches 63 severally and selectively removably interlocking with a pin 64 fastened and depending from the top wall 10. The gage bar 60 may be displaced transversely and longitudinally of the base B by gripping the upstanding paper stop 65. Lateral or transverse displacement is possible in that straps 61 and 62 provide a loose or sloppy fit about the bar 60, thus permitting a notch 63 if interlocked with the fixed pin 64 to be removed from the latter and thereafter slidably withdrawn or retracted as desired and again interlocked with another notch 63, however the bar cannot be completely withdrawn in view of the offset or bent out lug 65' adapted to cooperate with strap 61 which serves also as a stop.

With the gage bar set in an adjusted and interlocked relation with the fixed pin 64, it is maintained in such relation due to the action of the biased leaf spring LS which has one end spot welded to strap 61 and has its other free end indented to provide an arcuate lip 66, resiliently bearing against the uninterrupted face 76 of the gage bar, thereby holding the latter in its desired interlocked position.

The driving shaft 38 while retained in a rotatable relation with the headers or standards S is normally held against lateral withdrawal therefrom. To this end it will be observed (Figs. 3 and 6) that a floating pin or stud 70 is slidably mounted in the bore 71 in the drive shaft 38. This bore 71 terminates in enlarged sockets 72 and 73. The socket 72 defines with bore 71 an annular stop shoulder 74 which serves as a seat and limits downward displacement of the enlarged dome shaped head 75 of the floating pin 70 which has its lower end 76 enlarged and flared and is removably and completely receivable in the lower socket 73 but is prevented from entering bore 71 by reason of the annular shoulder 77. Normally the flared end 76 projects beyond the limits of the periphery of the drive shaft 38, thus serving as a projection disposed alongside of one of the standards S. Consequently the latter serves as a stop for the floating stud 70 thereby preventing lateral withdrawal of the drive shaft which can in fact be withdrawn from the standards if the locking and floating stud 70 has its flared end 76 manually moved into the socket 77. By such action the entire length of stud 70 is confined within the limits of the drive shaft, hence the latter can be slidably withdrawn from the standards. Thereafter, if desired, punches or punching members 23 may be replaced, and the drive shaft is operatively and rotatably interlocked with the substituted punches. However upon the insertion of the drive shaft into the substituted punches, it is desirable that the floating stud 70 be again lifted and held confined by finger pressure to be within the limits of the drive shaft 38 until the latter passes through the last standard, that is, the standard at the right hand part of Fig. 3 in which case the float or locking pin 70 drops by gravity, and its lower portion projects beyond the drive shaft as desired to co-

operate with the stop face 18 of the standard S at the right hand part of the base.

In the form illustrated in Fig. 41, the biased leaf spring 80 has one end 81 welded to the reduced ledge or flange 17 of the reinforcing block 15 and has another end or free terminal provided with an arcuate lip or detent 82 which is adapted to removably interlock or severally snap into the notches 63 of the gage bar 60, thus holding the latter in a set position against the spaced and fixed straps 61 and 62 which loosely and slidably guide the bar. Hence the latter may be slidably withdrawn until the offset lug 65 meets strap 61 or it may be conveniently set to interlock with one of its notches 63 with the dent end 82, thereby holding the gage bar in a desired set position.

During shipping of the perforating device P or during intervals when it is not in use, and it is desired that it take up as little space as possible, the handle H may be held depressed. In this connection it will be observed that arm 90 of the fixed handle H carries the fixed pin 91 which overhangs the inside face 92 of the arm and which is adapted to be brought under lobe 19 of the right hand standard when a thrust is imparted to arm 90 in a direction towards the standards. Since springs 34 constantly urge the punching tools in an upward direction, thus causing the drive shaft to be urged in a counterclockwise direction, the locking pin 91 will be maintained yieldingly under but against the adjacent fixed lobe 19, thereby preventing further upward movement of the handle. Or in other words, the handle is locked in a depressed position. To unlock the handle, the latter is grasped and bodily urged outwardly, thus bodily but slightly slidably displacing drive shaft 38 to the right, hence withdrawing the fixed locking pin 91 from the adjacent standard, and the handle is automatically unlocked, there being ample clearance between the floating and slidable pin 70 and this standard to permit such slight sliding action of the drive shaft 38 to allow the insertion of the locking pin 91 under the adjacent lobe 19 or permit removal therefrom.

To prevent marring of a supporting surface for the base, the latter includes corner lugs 93 to which rubber feet 94 are appropriately attached.

In the form according to Figs. 12-15, stud or pin 95 is fixed in the bore 74 communicating with groove 39 and its terminal 96 projects beyond shaft 38 to cooperate with transverse face 18 of the right hand standard to prevent withdrawal of the shaft which however may be withdrawn therefrom when terminal 96 is lined up with and drawn through gap 97 which communicates with bearing 37 and is coextensive with the width of the standard. By this arrangement shaft 38 when desired may be removed from or interlocked with the punching tools slidably guided by the standards. In other aspects, the embodiment of Figs. 12-15 is along the lines of the form according to Fig. 1.

Various changes may be made in details of construction and arrangement of parts without departing from the spirit of the invention or sacrificing any of the advantages thereof inherent therein.

I claim:

1. In a perforating device, an elongated and hollow base comprising a depending rim having spaced sides, reinforcing means disposed within said rim and extending substantially coextensive with the length of said base, between said sides and comprising spaced attenuated webs and in-

termidately disposed boss means integral with and between said webs, a standard on the outside of said base, fastening means extending through said boss means for removably clamping said standard to said base, punching means slidably guided by said standard, shaft means for driving said punching means, and a handle for actuating said shaft means.

2. In a perforating device, an elongated and hollow base comprising a depending rim having spaced sides, a reinforcing block disposed within said rim and extending substantially coextensive with the length of said base, between said sides and comprising spaced attenuated webs and in-termidately disposed boss means integral with and between said webs, means securing said block to said base, a standard on the outside of said base, fastening means extending through said boss means for removably clamping said standard to said base, punching means slidably guided by said standard, shaft means for driving said punching means, and a handle for actuating said shaft means.

3. In a perforating device, an elongated and hollow base comprising a depending rim having spaced sides and spaced front and rear walls, reinforcing means secured to said base within said rim and extending substantially coextensive with the length of said base between said sides and comprising spaced attenuated webs and in-termidately disposed boss means integral with and between said webs and interposed between said walls, a standard on the outside of said base, fastening means extending through said boss means for removably clamping said standard to said base, punching means slidably guided by said standard, shaft means for driving said punching means, and a handle for actuating said shaft means.

4. In a perforating device, an elongated and hollow base comprising a depending rim having spaced sides, an elongated block for reinforcing said base substantially coextensive with the distance between said sides and disposed within said rim, means for securing said block to said base, a standard on the outside of said base, fastening means partly within said rim and extending through said reinforcing means for removably clamping said standard to said base, punching means slidably guided by said standard, shaft means for driving said punching means, and a handle for actuating said shaft means.

5. In a perforating device, an elongated and hollow base comprising a depending rim having spaced sides, reinforcing means disposed within said rim and extending substantially coextensive with the length of said base between said sides and comprising spaced attenuated webs and in-termidately disposed boss means integral with and between said webs, a plurality of standards on the outside of said base, fastening means extending through said boss means for removably clamping said standards to said base, punching means slidably guided by said standards, shaft means for driving said punching means, and a handle for actuating said shaft means.

6. In a perforating device for punching sheet material, a base having a top wall including an opening and including a rim having spaced sides, a standard mounted on said wall, punching means slidably guided by said standard, said base and standard defining a gap for removably receiving said material, a shaft rotatably guided by said standard for driving said punching means across said gap and into said opening to per-

forate said material, a receptacle interposed between said sides and underneath said punching means for collecting punch leavings, and means swingably connecting said receptacle to said base, said sides and receptacle having means frictionally and removably engaging for holding said receptacle closed under said punching means.

7. In a perforating device for punching sheet material, a base having a top wall including an opening and having a depending rim embodying spaced sides, a standard mounted on said wall, punching means slidably guided by said standard, said base and standard defining a gap for receiving said material, a shaft rotatably guided by said standard for driving said punching means across said gap and into said opening to perforate said material, a receptacle within said rim and interposed between said sides and underneath said punching means for collecting punch leavings, means swingably connecting said receptacle to said sides, and detent means for frictionally locking said receptacle to said sides.

8. In a perforating device for punching sheet material, a base having a top wall including an opening and having a depending rim embodying spaced sides, a standard mounted on said wall, punching means slidably guided by said standard, said base and standard defining a gap for receiving said material, a shaft rotatably guided by said standard for driving said punching means across said gap and into said opening to perforate said material, a receptacle within said rim and interposed between said sides and underneath said punching means for collecting punch leavings, means swingably connecting said receptacle to said sides, and detent means for frictionally locking said receptacle to said sides, said punch means and leavings cooperating when said receptacle is filled up with said leavings to overcome the frictional resistance imparted by said detent means against said sides for automatically swinging said receptacle downwardly and away from said punching means to open said receptacle.

9. In a perforating device for punching sheet material and form punch leavings, a base having a top wall including an opening and including a depending rim embodying spaced sides, a reinforcing block within said rim and having a boss including a bore in registration with said opening, means securing said block to said base, a standard mounted on said wall, punching means slidably guided by said standard, said base and standard defining a gap for receiving said material, a shaft rotatably guided by said standard for removably driving said punching means across said gap and into said opening and bore to perforate said material, a receptacle within said rim interposed between said sides and underneath said punching means and normally closed against said block for collecting said leavings, means swingably connecting said receptacle to said sides to permit tilting of said receptacle towards and away from said block, and locking means to prevent opening of said receptacle.

10. In a perforating device, a base, a standard mounted on said base and having a bearing and a gap in communication with said bearing, punching means slidably guided by said standard, shaft means slidably and rotatably guided by said bearing for actuating said punching means, said shaft means having a bore, and a pin at least in part within said bore and said shaft means and normally out of alinement

75 with said gap and cooperating with said standard to prevent withdrawal of said shaft means therefrom, said terminal upon rotation of said shaft means adapted to be alined with said gap and completely drawn therethrough to permit the removal of said shaft means from said standard.

11. In a perforating device, a base, a standard mounted on said base and having a bearing, punching means slidably guided by said standard, shaft means slidably and rotatably guided by said bearing for actuating said punching means, said shaft means having a bore and upper and lower sockets defining with the wall of said bore upper and lower shoulders, and a pin having an intermediate portion slidably guided by said bore and having a terminal normally projecting beyond said shaft means to cooperate with said standard to prevent withdrawal of said shaft means therefrom, said pin having an enlarged portion adapted to be seated on said upper shoulder to limit the projection of said terminal beyond said shaft means, said terminal having an enlarged portion cooperating with said lower shoulder to limit the insertion of said terminal into said shaft means at which time said pin is completely within said shaft means.

12. In a perforating device, a base, a standard mounted on said base and having a bearing and including a lobe, punching means slidably guided by said standard and at least in part by said lobe, shaft means slidably and rotatably guided by said bearing for reciprocating said punching means, an arm, means fixedly holding said arm on said shaft means, spring means surrounding at least a part of said punching means for normally holding the latter and said arm elevated, and a projection extending from said arm and adapted to be removably positioned under said lobe to hold said arm depressed.

13. In a perforating device for punching sheet material, a base having a top wall including an opening and having a depending rim embodying spaced sides having spaced bearings, a standard mounted on said wall, punching means slidably guided by said standard, said base and standard defining a gap for receiving said material, a shaft rotatably guided by said standard for driving said punching means across said gap and into said opening to perforate said material, a receptacle within said rim and interposed between said sides and underneath said punching means for collecting punch leavings and having ears including nipples rotatably sustained by said bearings for swingably displacing said receptacle relative to said base, and spring detent means projecting from said receptacle for frictionally and removably engaging at least one of said sides, said punch means and leavings cooperating when said receptacle is filled up with said leavings to overcome the frictional resistance imparted by said detent means for automatically swinging said receptacle downwardly and away from said punching means to open said receptacle.

14. In a perforating device for punching sheet material, a base having a top wall including an opening and having a depending rim embodying spaced and vertically disposed sides having bearings, a standard mounted on said wall, punching means slidably guided by said standard, said base and standard defining a gap for receiving said material, a shaft rotatably guided by said standard for driving said punching means across said gap and into said opening to perforate said material, a receptacle within said rim and inter-

posed between said sides and underneath said punching means for collecting punch leavings and having spaced ears at one end of said receptacle and embodying nipples rotatably sustained by said bearings for pivotally displacing said receptacle relative to said base, and spring detent means struck out of said receptacle frictionally and disengageably cooperating with at least one of said sides, said punch means and leavings cooperating when said receptacle is filled up with 10 said leavings to overcome the frictional resistance imparted by said detent means for automatically swinging said receptacle downwardly and away from said punching means to open said receptacle.

15. In a perforating device for punching sheet material, a base having a top wall including an opening and having a depending rim embodying spaced sides having spaced bearings, a standard mounted on said wall, punching means slidably guided by said standard, said base and standard defining a gap for receiving said material, reinforcing means adjacent said top wall and within said rim and substantially coextensive with the length of said base between said sides, means 20 securing said reinforcing means to said wall, a shaft rotatably guided by said standard for driving said punching means across said gap and into said opening to perforate said material, a receptacle within said rim and interposed between said sides and underneath said punching means for collecting punch leavings and having projecting means, means rotatably sustaining said projecting means to said bearing means, and spring detent means projecting from and integral with said receptacle and cooperating with at least one of said sides for frictionally and disengageably holding said receptacle closed adjacent said reinforcing means, said punch means and leavings cooperating when said receptacle is filled 25 up with said leavings to overcome the frictional resistance imparted by said detent means against said sides for automatically swinging said receptacle downwardly and away from said punching means to open said receptacle.

16. In a perforating device for punching sheet material, a base having a top wall including an opening and having a depending rim embodying spaced sides having spaced bearings, a standard

mounted on said wall, punching means slidably guided by said standard, said base and standard defining a gap for receiving said reinforcing means adjacent said wall and within said rim and comprising spaced webs and boss means, said webs and boss means being substantially coextensive with the length of said base between said sides, means securing said reinforcing means to said top wall, a shaft rotatably guided by said standard for driving said punching means across said gap and into said opening to perforate said material, a receptacle within said rim and interposed between said sides and underneath said punching means for collecting said punch leavings and having spaced ears having nipples rotatably disposed in said bearings for swingably sustaining said receptacle relative to said base, and spring detent means struck out of said receptacle and cooperating with said sides for frictionally and disengageably holding said receptacle closed adjacent to said reinforcing means, said punch means and leavings cooperating when said receptacle is filled up with said leavings to overcome the frictional resistance imparted by said detent means against said sides for automatically swinging said receptacle downwardly and away from said punching means to open said receptacle.
